UNITED STATES PATENT OFFICE.

STILLWELL R. HARCOURT, OF CHICAGO, ILLINOIS; MARTHA D. HARCOURT ADMINISTRATRIX OF SAID STILLWELL R. HARCOURT, DECEASED.

PLAYER-PIANO MECHANISM.

Application filed November 1, 1922. Serial No. 598,262.

The present invention relates to tempo control mechanism for player pianos, and embodies improvements upon the construction of control mechanism forming the subject matter of my prior Patent #1,316,573 issued Sept. 3, 1919.

In standard player piano practice, a so-called "take-up" roll is provided for drawing the sheet of music down across the tracker bar in playing the selection, after which the sheet of music is re-wound on its original carrying spool. A pneumatic motor is provided to operate either the spool or the roll, in re-winding or playing, respectively, and the present invention is concerned with the control of this pneumatic motor. More specifically, the invention is concerned with the control of the motor during the playing operation, that is, while the motor power is being applied to the take-up roll.

The feeder bellows constituting the source of suction, are usually provided with a reservoir, which has as its purpose to maintain a steady and continual suction on the devices operated from the feeder bellows. An air line connects this reservoir with the motor, and it is also customary to interpose a governor in this air line between the reservoir and the pneumatic motor for maintaining a constant rate of rotation of the pneumatic motor, determined by a preliminary adjustment of the governor.

The present form of control means is particularly designed for temporarily retarding or accelerating a phrase in the music being played, entirely independently of the above governor control, so that it is possible to quicken the pace of the music for a moment, or to retard it, in order to get the most artistic effect, without interfering with the rate at which the piece of music as a whole is set to be played. The mechanism of my prior patent performs the control function of accelerating the speed of the pneumatic motor by temporarily shunting the governor above referred to; and performs the control function of retarding the speed of the pneumatic motor by throttling the suction connection leading thereto.

The improved mechanism forming the subject matter of the present application performs the control function of accelerating the speed of the pneumatic motor in the same manner; but performs the control

function of retarding the speed of the pneumatic motor by venting atmospheric air into the suction line leading to the pneumatic motor, instead of throttling this suction line as in my prior construction. I have found that this latter mode of control gives a nicer precision and mode of operation, for the reason that it does at no time interfere with the predetermined air as set by tempo and controlled by governor. A further advantage of this mode of control lies in the fact that it does not noticeably affect the pumping action, because substantially the same amount of air is vented into the system, the control valve merely venting the air into the system at an anterior point, instead of having it pass through the motor. It also requires only one valve-box compartment and one valve rod entering this compartment, and is otherwise advantageous over my prior construction.

Other features concerned with the construction of valve-box for performing this control function, will be set forth in the following detailed description of the invention. A preferred embodiment thereof, is illustrated in the accompanying drawing in which:

Figure 1 is a front elevational view of a player piano, embodying the features of my invention, part of the casing being removed in order to reveal the interior construction;

Fig. 2 is a front elevational view of the valve-box of my invention;

Fig. 3 is an elevational view of the same with the front cover removed therefrom.

Fig. 4 is a vertical sectional view taken on the transverse center line of the valve-box.

Fig. 5 is a fragmentary sectional view of the control buttons and actuating levers for operating the valve elements in said valve-box, and;

Fig. 6 is a vertical sectional view of the tempo control valve, taken on the line 6—6 of Fig. 1.

Referring first to Figure 1, it will be seen that there is illustrated a piano casing 6, the keyboard being shown as 7. Properly mounted in the lower part of the casing is a supporting-board 8, which carries the pumper bellows 9 and 10, operated by the pedals 11^a and the connected reservoirs 11 and 12 respectively. The passageway 13 connects the bellows 9 and the reservoir 11, 11^a

and a passageway 14 connects the bellows 10 and the reservoir 12. Each of the reservoirs is provided with a spring 15 to keep it normally distended, and it will now be understood that the suction impulses from the respective bellows cause a steady suction to be maintained by the reservoirs.

The action, with the details of which I am not concerned, is illustrated broadly at 10 16, and it will be seen that the reservoir 11 is connected with the wind-chest of the action by means of the air line 17.

A governor 18 is provided adjacent the reservoir 12, and a passageway 19 connects the interior of the governor with the reservoir. No detail description of this governor is necessary because it is an old and well-known element in the art. It is sufficient to say that upon its interior the movable board of the governor, which is constructed like a bellows, is provided with a valve 20, which more or less restricts the port 21 of the passageway 19, so that the greater the suction the greater will be the tendency to close the port, thus compensating, in a complementary way, for increased suction in the reservoir 12. It will thus be seen that, with the inlet to the governor of a determined size, the suction controlled by the governor will remain substantially constant.

A spring 22 tends to keep the governor distended.

In the upper part of the piano casing, 35 a rail 23 is mounted, and a roller-box 24 is set upon this rail, this roller box having mounted therein the music roll 25, the music spool 26 and the tracker 27, set in such position therebetween that the paper 40 passing from the spool to the roll may slide over the tracker. A pneumatic motor 28 is also mounted upon the rail 23, and, by means of transmission mechanism 29, the power of the shaft 30 of the motor is 45 conveyed to either the spool 26 or the roll 25.

Since this invention is not concerned with the rewinding of the music sheet, I shall assume, for the purposes of this description, that the transmission mechanism is in 50 such condition that the power of the motor is applied to the roll 25. That is the playing condition.

A suction tube 31 leads from the motor 55 28 and goes to a valve box 32, mounted upon the rail 23. As shown in Figures 3 and 4, this valve box has a single compartment 33. This compartment is connected with the governor 18 by means of an air line 36, in which a valve 37 is preferably 60 interposed. As shown in Fig. 6, the valve 37 is capable of various degrees of opening or closing, and is adapted to remain in any set position, being manually controlled by 65 means of a forwardly extending valve stem

50. A direct air line 38 leads from the reservoir 12 directly up to the valve box 32. By "directly" I mean to convey the idea that the air line 38 is a path of lower resistance than the air line 36, which includes the governor.

Referring now to the details of construction of this valve box 32, as shown in Figs. 2, 3 and 4, it will be observed that the valve box is of inexpensive wood construction, 75 of rectangular form, and has a removable front cover 34. Entering the two side walls of the box 32 are two short sections of metallic conduit or tubing 39 and 40. The conduit 39 receives the end of the suction tube 31, and the conduit 40 receives the end of the suction tube 36 extending up from the governor 18. Both of these conduits have direct and open communication with the valve compartment 33 at all times, 80 there being no valve controlling the communication of these conduits with the compartment 33. The "direct" air line 38 leading from the reservoir 12, has connection over the end of a section of tubular 85 conduit 41 which is rigidly mounted in the rear wall of the valve box 32. The communication between this conduit 41 and the compartment 33 is controlled by a vertically moving valve 42 which slides up and 90 down along the rear wall of the valve box 32, and is adapted to cover and uncover the opening of the conduit 41. The valve block 42 is guided laterally and is held to the face of the rear wall by a pair of resilient wires 43 which are anchored in the bottom of the valve box and which bear in vertical grooves 44 in the outer face of the valve block. The upper edge of the valve block 42 is provided with a long notch 45, forming a tapering valve port for obtaining 100 a gradual opening of the end of the conduit 41. A screw 46 is mounted in the back wall of the valve box in position to be engaged by the bottom of the notch 45 when the inner end of the conduit 41 is completely covered, this screw acting as a limiting stop for the upward closing motion of the valve block 42.

The valve is actuated by a rod 47 which 105 extends downwardly through the bottom of the valve box 32. The upper end of this rod 47 is bent laterally to engage in the valve block 42, and this end is held in the valve block by a pair of screws 48 which screw into the block on opposite sides of the rod 47 and have their heads overlying and confining the rod 47. This rod has a snug sliding fit in the bore in the bottom 110 of the valve box 32, so as to minimize air leakage, and the lower end of the rod is threaded at 49 for adjustable connection with an actuating lever which I shall hereinafter describe.

It will be observed that when the valve 115

block 42 is in its uppermost position, the conduit 41 is completely blocked, and consequently the compartment 33 is only subjected to the suction transmitted from the governor 18 up through the suction line 36. This means that the regulated suction from the governor 18 is effective at the pneumatic motor 28. When the valve block 42 is completely down, a relatively higher suction is effective in the compartment 33 through the direct communication between the conduit 41 and the reservoir 12. This higher suction is effective to run the pneumatic motor 28 at a higher rate of speed than that resulting from the regulated suction transmitted from the regulator 18. A nice graduation of this pneumatic motor speed can be obtained by the proper positioning of the notch-like port 45 for restricting the port opening of the conduit 41 to a greater or less degree.

For retarding the speed of the pneumatic motor 28, below that resulting from the supply of the regulated suction from the regulator 18 thereto, I propose venting atmosphere into the valve box compartment 33 by the motion of a reciprocatory valve 51 mounted on the front of the removable cover 34. The valve block 51 is guided between two vertical guides 52 on the cover 34, these guides being formed with flanges overlying the back of the valve block 51 for confining the latter against the face of the cover 34. The block 51 controls a port 53, of inverted T formation, extending through the removable cover 34 and communicating with atmosphere on one side and the valve box compartment 33 on the other side. The vertical stem portion of the T is comparatively narrow, so that when this portion is exposed, the admission of atmosphere will be more or less restricted, depending upon the length exposed. The cross bar portion of the T is relatively wide and deep, so as to afford a large atmospheric inlet when the valve block 51 is in its lower position. The upward motion of the valve block 51 is limited by a small block of felt 54, which is glued to the removable cover 34 between the upper end of the guides 52. The valve block 51 is actuated by a rod 55, passing through a bridge member 56 of felt which is glued across the bottom of the guide member 52. The upper end of the actuating rod 55 is threaded for screwing into a compressed block of felt or other material 7, which is glued to the back of the valve block 51. Strips of felt 58 are glued along each margin of the valve block 51 to engage with the overlying flanges of the guide members 52, for the purpose of maintaining a firm sliding fit, and to minimize leakage. The lower end of the actuating rod 55 is threaded at 59, similarly to the actuating rod 47, for connection with its actuating lever.

As shown in Figs. 1 and 5, each of the

valve actuating rods 47 and 55 is connected with a swinging lever 61, pivoted at 62 in back of the key-board. The threaded ends 49 and 59 permit adjustment of the valves 42 and 51 relative to the swinging levers 61. 70 The other end of each of the levers is provided with an actuating button, which is exposed through the key-slip. The button 64, which operates the valve block 51, may have any suitable mounting, but the button 63, which controls the movement of the valve block 42, has a special mounting illustrated in Fig. 5. The button 63 is pivotally mounted upon its lever 61, at 65, and the opening 66 in the key-slip, through which 80 the button extends, is of such size as to permit a slight lateral play of the button. The lower end of a spring 67 may be secured at 68 to the opposite end of the lever 61, whereby the lever 61 and button 63 are normally held in the raised position as shown in Figs. 1 and 5. The button itself is provided with a notch 71 which is adapted to cooperate with a catch 72, secured to the top of the key-slip and so disposed that 90 when the button 63 is depressed and moved slightly to the right, the notch will engage with the catch to hold the button 63 in its lowermost position against the tension of the spring 67 and to lock it in that position, 95 so that the valve 42 may be kept open without further attention if desired.

The operation of my device will now be clear. A certain tempo being ascribed to a piece of music to be played, the valve 37 is 100 primarily adjusted to correspond to the required rate. This rate, as before explained, is maintained by the operation of the governor 18, since, under normal conditions, the suction is applied to the motor exclusively 105 through the intervention of the governor, the valve 42 being completely closed, and the valve 51 also being closed. If it is desired to temporarily retard the tempo, the button 64 is correspondingly depressed, whereupon 110 the valve 51 is opened to a greater or less degree and atmospheric pressure is admitted to the compartment 33. This atmospheric pressure reduces the suction effective at the pneumatic motor, and if sufficient atmosphere is vented into the compartment the pneumatic motor may be stopped if desired. However, immediately upon the release of the button 64, the tempo immediately 115 returns to the rate as determined by the 120 valve 37.

When, on the other hand, it is desired to accelerate momentarily, the button 63 is depressed and the valve 42 is opened, thus temporarily transmitting the ungoverned 125 suction of the reservoir to the motor. Here, again, immediately upon the release of the button 63, the spring 67 closing the valve 42, causes the motor to return to its preliminarily-determined speed. If, as before 130

described, the button 63 is depressed and then moved slightly to its right, the valve 42 may be locked in its open position so that it will remain open without further attention 5 on the part of the operator. This throws the governor entirely out of use until the button is again released, and during such period it will be seen that the operator may govern the tempo by his own pumping, as 10 is frequently the case when the operator may, at the same time, be playing some other instrument.

I claim as new and desire to secure by Letters Patent of the United States:

15 1. In an automatic music instrument, the combination of note sheet means, a pneumatic motor for moving said note sheet means, a source of suction, a suction conduit connecting said source and said motor 20 for transmitting the suction from said source to said motor, and means for venting atmosphere directly into the suction connection between the source and motor to decrease the effectiveness upon the motor of 25 a given suction from said source without throttling the suction source or changing the suction therefrom.

2. In a player piano, the combination of note sheet means, a pneumatic motor for 30 moving said note sheet means, a source of suction, a suction conduit connecting said source and said motor for transmitting the suction from said source to said motor, means for venting atmosphere directly into 35 the suction connection between the source and motor to decrease the effectiveness upon the motor of a given suction from said source without throttling the suction source or changing the suction therefrom, and control means disposed adjacent the keyboard 40 of the piano for controlling said venting means.

3. In a player piano mechanism, the combination of a pneumatic motor, a source of 45 suction, conduit means connecting said source and motor for transmitting suction from said source to the motor, and valve mechanism interposed in said conduit means, said valve mechanism being operative to 50 transmit high and low suctions to said pneumatic motor and to vent atmosphere into the suction connection between the source and motor to retard the driving effectiveness of 55 a given suction upon the motor and thereby the speed of the motor without throttling the source or changing the suction therefrom.

4. In a player piano mechanism, the com-

bination of a pneumatic motor, a source of suction, a suction conduit connecting said source and said motor for transmitting the suction from said source to the said motor, means in said conduit for regulating the suction transmitted, and means for venting atmosphere directly into said suction conduit 60 to decrease the effectiveness of a given suction from said source upon the motor without changing the suction as regulated by said regulating means.

5. In player piano mechanism, the combination of a pneumatic motor, a source of suction, a low suction conduit, a high suction conduit, one of said conduits having valved control means for regulating the suction transmitted to the pneumatic motor, and 70 means for venting atmosphere directly into the low suction conduit connection between the source and motor for retarding the speed of the motor.

6. In player piano mechanism, the combination of an action, note sheet mechanism for said action, a pneumatic motor for operating said note sheet mechanism, a suction system supplying suction to said pneumatic motor and comprising a source of suction, a 80 suction reservoir, an air line connecting said pneumatic motor with said reservoir, a valve chest interposed in said air line, the air line between the valve chest and the reservoir being divided into two independent 85 branches, one of said branches having free and open connection with the reservoir, a governor interposed in the other branch, a valve in said valve chest controlling the connection of said branches with said pneumatic 90 motor, and means for venting atmospheric pressure into the air line to the motor through said valve chest to retard the motor 95 without throttling the suction from the source.

7. In piano player mechanism, an action, note sheet mechanism for said action, a pneumatic motor for operating said note sheet mechanism, a suction reservoir, an air line connecting said pneumatic motor and said 105 reservoir, a governor in said air line, a second air line connecting said motor directly with said reservoir, a manually operated valve in said second air line, and a manually operated valve for admitting atmosphere 110 directly into one of said air lines to control the effectiveness upon the motor of a given suction in said line.

In witness whereof, I hereunto subscribe my name this 27th day of October, 1922.

STILLWELL R. HARCOURT.
